US0D1075837S

(12) **United States Design Patent** (10) **Patent No.:** **US D1,075,837 S**
Austria et al. (45) **Date of Patent:** **** May 20, 2025**

(54) **DISPLAY SCREEN OR PORTION THEREOF
WITH A GRAPHICAL USER INTERFACE**

(71) Applicant: **Zoox, Inc.**, Foster City, CA (US)

(72) Inventors: **Auver Cedric Austria**, San Francisco, CA (US); **Riccardo Giraldi**, San Francisco, CA (US); **Andrew Allen Haskin**, San Francisco, CA (US)

(73) Assignee: **Zoox, Inc.**, Foster City, CA (US)

(**) Term: **15 Years**

(21) Appl. No.: **29/867,184**

(22) Filed: **Oct. 13, 2022**

Related U.S. Application Data

(62) Division of application No. 29/759,234, filed on Nov. 20, 2020, now Pat. No. Des. 971,255.

(57) **CLAIM**

The ornamental design for a display screen or portion thereof with a graphical user interface, as shown and described.

DESCRIPTION

FIG. 1 is a front view of a first embodiment of a display screen or portion thereof with a graphical user interface; FIG. 2 is a front view of a second embodiment of a display screen or portion thereof with a graphical user interface; FIG. 3 is a front view of a third embodiment of a display screen or portion thereof with a graphical user interface; and, FIG. 4 is a front view of a fourth embodiment of a display screen or portion thereof with a graphical user interface. The dot-dashed broken lines depict a boundary of the display screen or portion thereof or a boundary on the display screen and form no part of the claimed design. The dashed broken lines depict portions of the display screen or portion thereof with a graphical user interface which form no part of the claimed design.
